ATTORNEY

UNITED STATES PATENT OFFICE.

RUTH F. HOUGH, OF SIERRA MADRE, CALIFORNIA.

BONNET.

1,375,048.

Specification of Letters Patent. Patented Apr. 19, 1921.

Application filed May 27, 1920. Serial No. 384,647.

To all whom it may concern:

Be it known that I, RUTH F. HOUGH, a citizen of the United States, residing at Sierra Madre, in the county of Los Angeles 5 and State of California, have invented a new and useful Bonnet, of which the following is a specification.

This invention relates to a bonnet of a type capable of being opened flat for laundrying.

An object of the invention is to produce a one piece bonnet having an openable band fastened to a crown piece, and having a draw string encircling the crown piece so 15 that the bonnet can be adjusted to fit the head of the wearer. By this construction, when the ends of the band are disconnected and the draw string loosened, the bonnet can be readily laundered, since it can be 20 washed and ironed the same as any flat work.

Other objects and advantages will appear in the subjoined detailed description.

The accompanying drawings illustrate the 25 invention.

Figure 1 is a view of one side of a bonnet embodying the invention, the bonnet being open for laundrying purposes.

Fig. 2 is a view of the other side of the 30 open bonnet shown in Fig. 1.

Fig. 3 is an enlarged sectional elevation on line indicated by x^3-x^3 , Fig. 1.

Fig. 4 is a side elevation of the bonnet closed ready for wearing.

35 There is provided a crown-forming piece 1 having a curved edge 2 extending around substantially two-thirds thereof. The crown-forming piece 1 connects at 3 with the intermediate portion of a curved band-forming piece 4. The ends of the band-forming piece 4 extend beyond the junction of the intermediate portion 3 with the crown-forming piece to form flaps 5 which can be detachably connected with the curved 40 edge 2 by any suitable means. In this particular instance the edge 2 and the band-forming piece 4 are provided with coöperating 45 fastening means in the form of snap fasteners 6, 7, the members 7 being spaced at closer intervals than the members 6 so

50 that when the fastening members of the band-forming piece are engaged with those of the crown-forming piece the marginal portion of the crown-forming piece will be 55 full relative to the band-forming piece. The flaps 5 are provided with coöperating fas-

tening means so that said flaps may be connected to each other at their ends and for this purpose, in this particular instance, the fastening means comprise buttons 8 and button holes 9.

In the drawings the crown-forming piece 1 is formed from a single thickness of material and the band-forming piece 5 of two thicknesses, one of which is integral with 60 the crown-forming piece 1. The other thickness of material forms a facing 10 which, if desired, may be of different color and weave to lend a distinctive appearance to the bonnet.

The free edge or marginal portion of the crown-forming piece 1 is preferably provided with a hem 11 through which extends a draw string 12, though the draw string may be omitted, if the maker so elect. The 70 draw string 12 also extends between the two thicknesses of material comprised in the band-forming piece 4, there being spaced lines 13 of stitches and the draw string extending between said lines of stitches. The 75 end portions of the draw string 12 pass through an opening 13 in the intermediate portion 3 where the crown-forming piece 1 connects with the band-forming piece 4.

In Figs. 1 and 2 of the drawings the bonnet is shown opened for laundering, and to close the bonnet, and thus put it into the wearing condition shown in Fig. 4, the fasteners 6 will be engaged with the fasteners 7 and the flaps 5 will be buttoned together. 85 Then the ends of the draw string 12, if the bonnet be provided with such string, will be drawn to decrease the diameter of the bonnet sufficiently so that it will fit the head of the wearer. When the bonnet becomes 90 soiled, operations the reverse of those just described will be performed to open the bonnet so that it can be readily laundered.

It will be understood that, though the drawings show the crown-forming piece 1 and one of the members of the band-forming piece 4 constructed from a single piece of material, they may, if desired, be made of separate pieces sewed together in a manner readily understood in the dressmakers' 95 art.

I claim:

1. A bonnet comprising a band-forming piece, a crown-forming piece connected with the intermediate portion of the band-forming piece, releasable fastening means on the opposite ends of the band-forming piece,

- and other releasable fastening means on the band-forming piece and marginal portion of the crown-forming piece.
2. A bonnet comprising a band-forming piece, a crown-forming piece connected with the intermediate portion of the band-forming piece, the end portion of the band-forming piece forming flaps, releasable fastening means for the flaps, releasable fastening means on the band-forming piece and marginal portion of the crown-forming piece, and a draw string in the free edge of the crown-forming piece and in the intermediate portion of the band-forming piece.
- 15 3. A bonnet comprising a curved band-forming piece, a crown-forming piece having a curved edge and connected along a

portion of its margin with the intermediate portion of the band-forming piece, the end portions of the band-forming piece extending beyond the connection between the crown-forming piece and the band-forming piece, releasable fastening means on the ends of the band-forming piece, and coöoperating fastening means on the band-forming piece and free marginal portion of the crown-forming piece.

Signed at Los Angeles, California, this 20th day of May, 1920.

RUTH F. HOUGH.
